SEWING KIT

Helene Schildkraut, Hewlett, N. Y.

Application September 5, 1951, Serial No. 16,514

Term of patent 3½ years

(Cl. D3—19)

To all whom it may concern:

Be it known that I, Helene Schildkraut, a citizen of the United States of America, residing at town of Hewlett, in the county of Nassau and State of New York, have invented a new, original, and ornamental Design for a Sewing Kit, of which the following is a specification, reference being had to the accompanying drawing, forming part thereof.

In the drawing

Fig. 1 is a top plan view of a sewing kit showing my new design;

Fig. 2 is a front view; and

Fig. 3 is an exploded front view of the component parts comprising the sewing kit.

I claim:

The ornamental design for a sewing kit substantially as shown, and described.

HELENE SCHILDKRAUT.
